UNITED STATES PATENT OFFICE

171,192

COIN BANK

Frank W. Bower, Goshen, Ind.

Application June 5, 1953, Serial No. 25,354

Term of patent 14 years

(Cl. D34—11)

To all whom it may concern:

Be it known that I, Frank W. Bower, a citizen of the United States, residing at Goshen, in the county of Elkhart and State of Indiana, have invented a new, original, and ornamental Design for Coin Bank, of which the following is a specification, reference being had to the accompanying drawing, forming a part hereof.

The dominant features of my new design are shown in solid lines in the drawing. The center portion of the coin bank in Figures 1 and 2 is diagonally lined to indicate transparency.

I claim:

The ornamental design for a coin bank, as shown and described.

FRANK W. BOWER.
